J. Pettibone.

Fire Place.

Patented Oct. 28, 1808.

Daniel Pittibone. Letters Patent.

The subject referred to in these letters Patent & making part of the same, containing a description in the words of the said Daniel Pittibone himself of his "Warming Air-Stove."

The invention of this improvement of the warming air-stove consists in the construction of a stove or fire place with a large warming air-refuel made of cast iron, brick-work or other suitable substance with an air-pipe to admit the fresh air from the street or yard into said air-refuel where it is warmed & then transmitted by other air-pipes fixed into the top of said air-refuel into the room or apartment to be warmed. The air-refuel is made perfectly tight so that the smoke cannot enter into it or collect in the stove or fire place so that the flame circulates completely round all parts of it. The tube or pipe that conveys the fresh air into said air-refuel is fixed in at its bottom, & is of a size much larger than the pipe to transmit the warm air. The said air-refuel is fixed inside of the stove or fire place in such a manner that the higher the flame rises in the stove the more intensely the fire operates on it as the inside of the stove gradually approaches from its bottom to its top of the outside surface of said air-refuel, & compels the flame to reverberate against it. When the flame & smoke have risen to the top of the stove they are then obliged to descend over a partition in the stove forming a flue with the side of the stove, down as low as the gate of the fire place, & are then carried off into the chimney by a funnel. This construction prevents the heat from escaping into the chimney as it does in common iron stoves or fire places. The flame may also be made to pass through the center of the stove, so as to have the air-refuel com-

placed between the stove & the brick work on each iron
bar which goes round the stove. The furnace is preferable.
A tube may be fixed up leading from the room to be
heated with expel air to the grate of the fire place
of the stove so as to supply the fire with a current of air to make it burn
& at the same time draw out of said room the cold air. These tubes or
pipes are furnished with valve with the stove & are opened & shut by
hand in a manner similar to a common trapcock. The tube to
convey the warm air has a number of branches, after it has extended
from the stove to a proper distance; & these tubes are ^{round} carried to
various parts of the room & at such distances from the floor as
may be found necessary so as to warm all parts of the room & like
fresh air rarefied in this manner is transmitted into a room
will preserve the goodness & elasticity of the air & render the
room with very agreeable & healthy, ^{very comfortable} company to
people whose business require a good degree of warmth in their
rooms & apartments; & especially to people of consumptive con-
stitutions this kind of warmth will be found very agreeable
& salutary. Stoves made so large as to have air vessels to contain
40.5 or more gallons of air will be adequate to the warming several
rooms or apartments with one fire. These warm air pipes may
be made of tin, excepting about 2 feet of them which should be
of cast iron, & which go thro' the stove into the air vessel. These
tubes ought to be boxed or cased with other tin tubes or with
brass ones so as to prevent the cold air thro' which they pass
from cooling them. The stove has doors to the fire place & grates,
& also a damper to the funnel so as to regulate the heat & move
the fire. The shape of the stove may be round or square; but
the globular form is preferable. The stove of the globular
form containing this improvement will produce more
heat from the same quantity of fuel than any other shape.
With this form the said air vessel as well as the stove itself

being made of several half globes of cast iron a little concave & convex to shut together, can with ease be put together & rendered perfectly tight with a little binding made of brass & the whole of copper put in to wind around when the said reflect & stove are put together. In this globular stove the said air vessel is placed much higher than the top of the stove than any other part of it, so that the fire is driven very forcibly against all parts of the surface of said air vessel & the smoke is carried down from the top of the stove by a partition, which is fitted to the concavity of the stove, & is bent into the furnace as low down as the gutter. A stove of this form with an air vessel not larger than a common large iron tea kettle will produce a sensible good effect. The size however may be as required. The said air vessel ought to be as large as the magnitude of the stove will conveniently admit, & the said air pipe made in due proportion & well fitted so as to render said air vessel perfectly air tight, tubes excepted. These air vessels and tubes may also be fitted into common chimneys a little above the smoke box without disfiguring the fire place & will produce a good effect in warming the room. The same principles of rarefying air as above laid down may be applied in the construction of the lamps or small stoves to be lighted & heated by oil lamp for in this case the air tubes extend but one end or two from the sides of the lamp or stove. These are very convenient in case of sickness in the night time.
